DESIGN FOR A STOVE.

Design No. 12,605, dated December 20, 1881.

Cut. 250.

UNITED STATES PATENT OFFICE.

H. CLAY BASCOM AND CYRUS A. HODGES, OF TROY, N. Y., ASSIGNORS TO N. S. VEDDER PATTERN WORKS, BASCOM, GALBRAITH & CO., OF SAME PLACE.

DESIGN FOR A STOVE.

SPECIFICATION forming part of Design No. 12,605, dated December 20, 1881.

Application filed November 17, 1881. Term of patent 7 years.

To all whom it may concern:

Be it known that we, H. CLAY BASCOM and CYRUS A. HODGES, each a citizen of the United States, residing in the city of Troy, in the county of Rensselaer and State of New York, have jointly invented and produced a new and original Design for a Stove, of which the following is a specification, reference being had to the accompanying cut, print, or engraving 10 of a stove embodying said new design.

The design for the cap A consists of the flat top end parts, *b b*, having rounded end edges *c c*, in combination with the middle quadrilateral pyramidal portion, *D*, having truncate 15 upper corners, *e e*, and sides *f f*, curved concavely, and formed with the compound sprig ornaments *g g*, all shaped and arranged so as to appear as represented in the aforesaid print.

The design for the doors *H* consists of the 20 representation of a butterfly, *i*, on a sprig, *j*, upon the middle part of the rectangular panel *k*, having the upper corner ornaments, *l l*, and lower corner ornaments, *m m*, all shaped and arranged substantially as represented in the 25 accompanying engraving.

The design for the upper front side plate, *N*, consists of the rectangular panel *o*, having thereon the compound central sprig ornament, *p*, the cruciform upper corner ornaments, *l' l'*, 30 and the sprig-form lower corner ornaments, *m' m'*, all shaped and arranged together as shown in the aforesaid cut.

The design for the front door, *Q*, consists of the upper panel, *R*, having its surface curved 35 convexly upward and rearward, and formed with the series of mica lights *s*, having rectangular bottoms and reversely-curved tops, and the intermediate and lateral ornaments, *t*, in combination with the lower panel, *U*, having

its surface flat and vertical, and formed with 40 the series of draft-openings *v*, narrower and of greater numbers than the mica lights *s*, and having rectangular lower parts and reversely-curved arched tops, and the lateral and intermediate ornaments, *w*, all shaped and arranged 45 together as represented in the aforesaid print.

The design for the legs consists of the downwardly-reduced and concavely-curved lower portion, *X*, in combination with the downwardly-tapering upper part, *Y*, having concave side edges, *x x*, and its front face, *y*, furnished with the combined butterfly and sprig ornament *z*, all shaped and arranged as shown in the aforesaid cut.

What we claim as our joint invention is— 55

1. The design for the cap *A*, composed of the parts *b b c c D e e f f g g*, all shaped and arranged together as shown and described.

2. The design for the doors *H*, composed of the parts *i j k l l m m*, all shaped and arranged 60 together as set forth.

3. The design for the upper front side plate, *N*, consisting of the parts *o p l' l' m' m'*, all shaped and arranged as shown and described.

4. The design for the front door, *Q*, composed 65 of the parts *R s t* and *U v w*, all shaped and arranged together as shown and described.

5. The design for the legs, composed of the parts *X Y x x y z*, all shaped and arranged together as set forth. 70

In testimony whereof we hereunto set our hands, in the presence of two subscribing witnesses, this 15th day of November, 1881.

H. CLAY BASCOM,
CYRUS A. HODGES.

Witnesses:

AUSTIN F. PARK,
JAMES T. GOODFELLOW.
